(57) **CLAIM**

The ornamental design for the light duty cart, as shown and described.

DESCRIPTION

FIG. 1 is a left side view of the light duty cart, the right side view being a mirror image of the left side view.

FIG. 2 is a front elevational view of the light duty cart shown in FIG. 1.

FIG. 3 is a rear view of the light duty cart shown in FIG. 1.

FIG. 4 is a top view of the light duty cart shown in FIG. 1; and,

FIG. 5 is a bottom view of the light duty cart shown in FIG. 1. The portion of the cart shown in broken lines in FIGS. 1-5 is for the purpose of illustration and forms no part of the claimed design.

1 Claim, 4 Drawing Sheets
